Patented Nov. 14, 1916.

Marion G. Norris Inventor

By W. J. Fitzgerald & C
Attorneys

UNITED STATES PATENT OFFICE.

MARION G. NORRIS, OF POND CREEK, OKLAHOMA.

WRENCH.

1,204,480.

Specification of Letters Patent. Patented Nov. 14, 1916.

Application filed May 16, 1916. Serial No. 97,825.

To all whom it may concern:

Be it known that I, MARION G. NORRIS, a citizen of the United States, residing at Pond Creek, in the county of Grant and State of Oklahoma, have invented certain new and useful Improvements in Wrenches; and I do hereby declare the following to be a full, clear, and exact description of the invention, such as will enable others skilled in the art to which it appertains to make and use the same.

My invention relates to new and useful improvements in wrenches and is particularly adaptable for rotating pipes, bolts, nuts, and the like, and my object is to provide a hollow handle section to which is attached a fixed jaw.

A further object is to provide a jaw for coöperating with the fixed jaw and slidably mounted in the handle section.

A further object is to provide a lever adapted to coöperate with the shank of the movable jaw for holding the same in adjusted position.

A further object is to provide a screw driver at the free end of the lever. And a further object is to provide means for normally holding the lever in fixed position in line with or at right angles to the handle section whereby said handle section may be used for rotating the lever when used as a screw driver.

Other objects and advantages will be hereinafter set forth and more particularly pointed out in the accompanying specification.

In the accompanying drawings which are made a part of this application, Figure 1 is a longitudinal sectional view of the wrench showing the jaws and operating lever therefor in side elevation. Fig. 2 is a transverse sectional view as seen on line 2—2 of Fig. 1. Fig. 3 is a similar view as seen on line 3—3 of Fig. 1, and Fig. 4 is a similar view as seen on line 4—4 of Fig. 1.

Referring to the drawings in which similar reference numerals designate corresponding parts throughout the several views, 1 indicates the handle section which is preferably rectangular in cross section and hollow, a portion of the end wall of the handle section being removed to form an opening 2 for the reception of a movable jaw 3, said movable jaw having a shank 4 adapted to slide lengthwise of the handle section, the

length of the shank being substantially one-half the length of the body portion. The movable jaw 3 is held in perfect alinement with the handle section by extending a pin 5 transversely of the movable jaw, the ends 6 of the pin being entered in slots 6 in the side walls of the handle section.

Coöperating with the movable jaw 3 is a fixed jaw 4, one end of which is entered through the opening 2 between the side walls 6 of the handle section and at one end thereof, the end of the jaw entering the handle section having a seat or shoulder 8 which engages the top wall of the handle section, said jaw being secured to the handle section by 70 extending rivets 9 transversely through the side walls of the handle section and through the interposed portion of the fixed jaw.

One edge of the shank is provided with a plurality of notches 10 with which engage 75 teeth 11 carried by the lever 12, said lever having a circular head 13 at its inner end through which extends a pivot 14, the adjacent end wall of the handle section being removed to permit the lever to readily swing 80 into alinement with the handle section and shank or at right angles thereto, the pivot 14 extending through the side walls of the handle section at a point between the ends 85 of the handle section. One face wall 15 of the notches is at right angles to the trend of the shank, while the opposite wall 16 of each notch is preferably S-shaped or composed of two oppositely extending curves, 90 while the walls 17 of the teeth 11 are likewise at right angles to the trend of the lever and the walls 18 thereof similarly curved to the wall 16 of the notches 10, the straight walls of the notches and teeth coöperating 95 with each other to hold the movable jaw in fixed position, while the curved walls of the notches and teeth permit said teeth to readily enter or leave the notches.

The end of the lever 12 is extended a distance beyond the end of the handle section 100 1 and is preferably provided with a screw driver point 19, and in order to hold the lever in alinement with the handle section, or at right angles thereto so that the handle section may be used as a lever or handle for 105 rotating the lever when used as a screw driver, the curved face of the head 13 is provided with recesses 20 and 21 with which is adapted to engage a spring detent 22 fixed 110 to the adjacent end wall of the handle sec-

tion 1, the free end of the detent extending between the side walls of the handle section so that when the lever is in alinement with the handle section or in the position shown in Fig. 1, the end of the detent will be in engagement with the recess 20, while when the lever is swung to right angles to the handle section, the detent will engage the recess 21 and hold the same against lateral swinging movement while the lever is being used as a screw driver, the handle section 1 serving as a cross head or handle for rotating the screw driver and said detent will also serve to hold the lever in fixed position and out of alinement with the shank while the movable jaw is being adjusted.

The meeting faces of the jaws 3 and 7 are preferably provided with serrations 23 and 24 respectively on the portions thereof projecting beyond the handle section so that a round object, such as a pipe, bolt, or the like, may be readily rotated by the wrench.

In applying this form of wrench to use, the lever 12 is swung outwardly until the teeth 11 are out of engagement with the notches 10 and the object to be rotated positioned between the jaws 3 and 7, when the lever is again swung inwardly and the teeth thereon entered in corresponding notches in the shank 4, the inward swinging movement of the lever forcing the movable jaw into engagement with the object between the jaws and by providing the spring detent, the jaw 3 will be held against movement in either direction until the teeth 11 are again disengaged therefrom. The object in projecting the free end of the lever beyond the end of the handle section not only permits the lever to be used as a screw driver, but said projecting end can be readily grasped for releasing the teeth 11 of the lever from the notches 10 of the shank.

Copies of this patent may be obtained for five cents each, by addressing the "Commissioner of Patents, Washington, D. C."

This form of wrench can be very cheaply constructed and may be made in various sizes as occasion may require and as all the parts are constructed of metal, it will be practically indestructible from use. It will also be seen that the wrench structure may be used in vise formation for holding articles of various kinds and by extending the free end of the lever 12 beyond the end of the handle section, the projecting portions of the lever may be readily grasped for swinging the lever on its pivot for disengaging the teeth from the notches. 55

Having thus fully described my invention what I claim as new and desire to secure by Letters Patent of the United States, is:—

In a wrench structure, a handle section, a fixed jaw carried by the handle section, a sliding jaw coöperating with the fixed jaw, a shank integral with the movable jaw, said shank having notches formed therein, a lever having a head pivotally mounted in the handle section, teeth formed on said lever adapted to engage the notches of the shank, said lever head being provided with recesses, and a spring detent fixed to the handle section and adapted to selectively engage the said recesses, said detent when engaged in one of said recesses serving to hold the lever in locked engagement with the movable jaw to prevent movement of the movable jaw with respect to the fixed jaw. 70 75

In testimony whereof I have signed my name to this specification in the presence of two subscribing witnesses.

MARION G. NORRIS.
